UNITED STATES PATENT OFFICE

2,612,130

CONCAVE BOTTOM HULL CONSTRUCTION

Johannes H. Wendt, Williams Bay, Wis.

Application August 16, 1949, Serial No. 110,560

2 Claims. (Cl. 114—62)

1

The present invention relates to universal boats, and is particularly concerned with the provision of an improved boat, the structure and design of which is adaptable universally; that is, for use as a row boat, a power boat, or a sail boat.

One of the objects of the invention is the provision of an improved boat structure which is capable of universal use in all of the three fields of boating, as a row boat, as a power boat, and as a sail boat.

Another object of the invention is to place within the means of a greater number of the public an improved boat structure which, although initially purchased as a row boat, may later be supplemented with a motor for use as a speed boat and may also be supplemented with attachments by means of which it is transformed into a sail boat, and the structure of which is advantageous for all three of these phases of boating.

Another object of the invention is the provision of an improved boat structure which is light, durable, capable of economical structure, has a minimum resistance to forward movement, has a maximum resistance to tipping, which tends to plane on top of the water when properly loaded, and which may be provided with a detachable weighted keel so that it may be used as a sail boat with maximum efficiency in all of its uses.

Another object is the provision of an improved detachable keel structure for boats, by means of which the stability of the boat may be increased and by means of which it may be provided with a weighted keel, as distinguished from a center board.

Other objects and advantages of the invention will be apparent from the following description and the accompanying drawings, in which similar characters of reference indicate similar parts throughout the several views.

Referring to the drawings, of which there are four sheets,

Fig. 1 is a top plan view of a boat embodying the invention;

Fig. 2 is a side elevational view;

Fig. 3 is a diagrammatic view, taken on the plane of the line 3—3 of Fig. 2, looking in the direction of the arrows;

Fig. 4 is a fragmentary elevational view, taken on the plane of the line 4—4 of Fig. 6, showing the details of attachment of the detachable keel;

Fig. 5 is a fragmentary sectional view, taken on the plane of the line 5—5 of Fig. 4;

2

Fig. 6 is an enlarged sectional detail view similar to Fig. 3, showing the details of construction of the hull of the boat and the arrangement of the frames;

Fig. 7 is a fragmentary sectional view, taken on the plane of the line 7—7 of Fig. 6, looking in the direction of the arrows;

Fig. 8 is a fragmentary sectional view, taken on the plane of the line 8—8 of Fig. 6, looking in the direction of the arrows;

Fig. 9 is a fragmentary detail view of the hull structure at the center line of the bottom, on a larger scale than Fig. 6;

Fig. 10 is a fragmentary top plan view of the stern of the boat, showing the motor and rudder bracket;

Fig. 11 is a fragmentary side elevational view of the stern of the boat, showing the mode of attachment of the rudder to the boat;

Fig. 12 is a fragmentary sectional view, taken on the plane of the line 12—12 of Fig. 1, looking in the direction of the arrows, showing how the oar locks are attached.

Fig. 13 is a larger cross-sectional view taken on the plane of line 13—13, Fig. 2, looking in the direction of the arrows.

Referring to Figs. 1 and 2, 20 indicates in its entirety my improved boat, which is preferably constructed of one of the light metals, such as Duralumin, but is capable of being constructed of any suitable material, such as wood, other metals, plastics, plywood, etc.

The embodiment which has been selected to illustrate the invention is constructed of the light metal mentioned, with the exception of certain of the parts, such as the seat, decks, mast, and rudder, which are preferably made of wood; and the weight of the detachable keel 21 may be made of solid iron or of a steel shell filled with lead.

The body of the boat is preferably constructed of a plurality of the light metal panels reinforced and supported upon suitable metal frames and riveted together by means of inside and outside overlapping strips, as will be described in detail with respect to Fig. 6.

The shape of the boat is preferably substantially as shown, for the purpose of increasing its stability against over-turning, reducing its resistance to forward motion, and also substantially increasing its resistance to lateral drift. For example, a cross section on the line 3—3 is shown in Fig. 3; and the bottom of the boat is preferably in the form of four separate metal panels 22, 23, 24, and 25 for the reason that

these panels are to be curved substantially along the lines which are shown in Fig. 2. For example, the line 26 indicates the water line, while the line 27 indicates the juncture between the panel 22 and the side panel 28 or the juncture between the panel 25 and the other side panel 28.

The panels 22 and 25 of the bottom preferably extend diagonally downward and inward at an obtuse angle, approximating in a general way the curvature of a sail boat, at this point. The juncture between the panels 22 and 23 is indicated at 30 and that between the panels 24 and 25 at 31.

At 30 the panel 23 is secured to the panel 22 in such manner that panel 23 extends diagonally upward and inward to the center line of the boat 32, where it joins the panel 24. Panel 24 also extends diagonally upward and inward from the juncture 31. The juncture between the panels 23 and 24, at 32, may be substantially at the same level as the corners 27. As distinguished from a round bottom boat, it will thus be observed that the panels 23 and 24 define a kind of elongated tunnel extending below the bottom of the boat at its central portion. Panel 24 is so disposed that it is practically normal to the water which it engages, when the boat is tipping, due to a downward force on the right side, or starboard.

Panel 23 is so positioned that it is normal to the direction of movement against the water, in the event of a tipping movement or force downward, applied on the left, or port side. Thus the arrangement of the bottom panels 23 and 24 is such that they present a maximum resistance to tipping.

When the boat is being operated as a speed boat, these panels assist in bringing the boat up to the top of the water, to effect a planing action, and give increased stability while the boat is planing.

The line 27 of Fig. 2 indicates the corner 27 in Fig. 3; and it will be noted that the shape of the side panels and bottom panels is such that this corner curves downward from both ends to the maximum lower position, midway of the ends of the boat.

The line 33 (Fig. 2) indicates generally a bottom line corresponding to the outside of the juncture 31, which also includes a runner carried at such juncture. Thus the shape of the bottom panels 24 and 25 and 22 and 23 is such that their apex is curved along the line 33.

Referring to Fig. 9, this disclosure of the structure at the juncture between the panels 23 and 24 shows in general how all panels may be joined together. A pair of elongated overlapping plates 34 and 35 are provided, which are bent along their midline, indicated at 32, to correspond to the angle at 32 in Fig. 3.

These plates have a special cement between them and the panels 23, 24 for waterproofing; and the plates 34, 35, 23, 24 are all riveted together by means of the two lines of rivets 36, 37. At regularly spaced intervals the bottom panels are riveted to the horizontal flange 38 of an angle iron which is riveted to transverse frame member 39, which may be in the form of an angle with a double flange 83 and a vertical flange 82.

These frame members 39 extend to the sides of the boat, where their vertical flanges 40 overlap the side frame members 41, to which they are riveted at 42. The vertical flanges 40 of the frames 39 are cut away at the junctures 30 and 31 and welded together to form a frame, with a suitable angle at 30 and 31. These frame members may also be provided with a slit in their vertical

flanges 40 at the mid-point 32 so that they may be bent downward to conform to the bottom panels 23, 24; and the slit may be filled with a gusset 43 forming part of flange 82.

At the juncture between the panels 22 and 23 or 24 and 25 the frame member 39 may have its horizontal flange 38 cut away to make room for the longitudinally extending plates 44, by means of which these panels are riveted together with waterproofing cement between the layers. At this point the bottom of the boat is provided with a pair of wooden runners 46, 47, which serve the purpose of supporting the boat, preventing damage to the hull when it is being slid into or dragged out of the water, increasing its stability against tipping, increasing its resistance to lateral drift, and providing means for attachment of the detachable weighted keel.

The runner 46 is similar in construction to runner 47, and both preferably taper downwardly from the top to the point 48, where they are provided with a more pronounced taper and with a rounded bottom 49. The top of each runner has an obtuse V groove 50, fitting the shape of the overlapping plate 45; and through bores 51 are provided at regularly spaced points for receiving the screw bolts 52, by means of which the runners are secured to the hull.

The heads of the screw bolts are countersunk in the bottom 49 of the runner; and the threaded end of the screw bolt 52 carries a special obtuse V washer or clamping plate 53, the bottom 54 of which fits the inside of the boat at this point. As the bottom of the boat is curved from front to back along the line 33, the runners are also curved; but they may be made of straight stock that is curved and held in curved position by being secured to the boat.

The runners 46 and 47 are cut away to form a substantially rectangular slot 55 at two places in each runner for attachment of the detachable keel unit 21, as shown in Fig. 4. The length of the slot 55 is such that it permits the frame members of the detachable keel to slide off the ends of the securing bolts 56 before they engage the end 57 of the slot.

The runner is preferably reinforced by a metal plate 58, beginning at each end of the slot 55, and secured to the bottom of the runner by wood screws 59.

The screw bolt 56 has a threaded end portion 60 projecting into the slot 55, but has its attaching flange portion 61 in the form of a thick plate, which may be of the same cross section as the rabbeted recess 62, in which it is secured in the runner. This makes the attaching portion 61 of the screw bolt 56 substantially trapezoidal, coming out flush with each side of that part of the runner which has maximum taper.

The screw bolt carries a nut 63, which is apertured to receive a cotter pin that also passes through the threaded portion of the screw bolt. The attaching portion 61 of the screw bolt 56 is secured to the runner and to the bottom of the boat by the screw bolts 52; and it should be understood that wherever a part is intended to be permanently secured together, rivets may be substituted for screw bolts.

The detachable keel unit 21 is shown in plan in Fig. 1, side elevation in Fig. 2, and end elevation in Fig. 3. The weighted keel portion 65 of this unit comprises an elongated, substantially flat metal body, which is oval and rounded at its ends, except that the front end 66 preferably points upward, while the rear end 67 has its point downward. This is for the purpose of permitting

the front end to over-ride obstructions which it might engage.

The body 65 is preferably made of a heavy metal, and may be cast iron or it may be a shell of aluminum or steel filled with lead. It is supported at each side by a pair of outwardly spreading legs 68, 69, 70, and 71. These legs preferably extend backwardly and downwardly toward the rear, while also spreading outwardly and upwardly from the body 65.

The top of each of the legs 68, 69 is joined by a bracing strut 72, 73 to the bottom of the legs 70, 71. The parts 68-73 are all preferably made of a metal tubing which is streamlined in shape; that is, generally formed with a rounded blunt forward edge and a more sharply curved trailing edge.

Since additional weight may be of advantage, these parts may be made of welded steel tubing; and the ends of the legs 68-71 may be welded to the iron or steel body 65. At their upper ends the four legs 68-71 are turned vertically upward at the attaching portion 74 of each leg and provided with a through bore 75 extending horizontally and located to receive the screw bolts 56, of which there are four, two on each runner.

Thus the keel may be attached by moving its attaching end portion 74 into the slots 55 and then moving the frame of the keel so that the bores 75 receive the bolts 56. The frame is then secured by nuts 63 and locked with cotter pins.

By means of the depending frame 68-73 the relatively flat weighted keel body 65 is supported vertically below the center line of the boat at such a low position that it acts like the weighted keel of a sail boat, tending to counter-balance the boat against tipping, and also permitting the pressure of the water on the keel to counter-balance the pressure produced by the wind on the sails.

Since such a weighted keel is available, a purchaser may first purchase a hull, which is usable as a row boat; and at a later date, when funds are available, he may transform it into a sail boat by purchasing the mast, boom, and sail, and the detachable keel. The same boat may, however, be used for rowing and fishing in shallow waters by removing the keel at any time.

The side frame members 41 are shown in section in Fig. 7; and they are preferably in the shape of a square Z with a double back flange on the inside. For example, each of these frame members 41 (Fig. 7) has a flat body 76 and a transverse attaching flange 77, which is riveted to the side panel 28 or 29.

On the inside of the frame member 41 the transverse flange 78 is preferably bent back upon itself at 79, having a doubled flange 80.

The top flanges 83 of the bottom frame members 39 may support a suitable floor rack. At their upper ends the side frame members 41 are supplemented by means of a deck plate 84, which may be made of the same material as the front and rear decks 85, 86. These front and rear decks and deck rails 84-86, when made of wood, are secured by means of bolts to transversely extending deck frame members 87 located at regularly spaced points, arching upward in the middle for drainage, and being of substantially T shape in cross section.

The deck frame members 87 are riveted at their ends to side frame members 41. The side frame members 41 also support a pair of wooden rails 88 on the inside and 89 on the outside, secured to the side frame members by means of through

bolts and rivets, and to which the deck rail 84 may be secured by means of wood screws.

The side frame members 41 also support suitable horizontally extending angle members 90 for supporting each end of the seats 91, 92, 93, which are preferably made of wood or non-metallic material, to avoid the high temperatures that are attained when metal is used.

A suitable lower block 94 is provided for receiving the end of a mast 95, which is also held at the deck 86 by means of a U-shaped clamping member 96, having two threaded ends which pass through a deck frame member 87, where the legs are secured by nuts.

The forward deck 86 preferably terminates in an obtuse V-shaped outline 97 at its rear edge. The side panels 28, 29 are curved laterally from front to back and curved inwardly at the bow to join with the bottom panel along a pair of line indicated at 98.

At the stern of the boat the upper edge of the side panels 28, 29 is preferably drawn inwardly, making the deck 85 narrower than the bottom of the hull. The stern of the boat is covered by a pair of stern panels 99, 100 (Fig. 1), riveted in place and secured to transverse frame members, and drawn inwardly toward the rear deck 85 at the top so that the bottom of the hull is longer than the deck at this point.

While the stern is thus not shaped to support an outboard motor, the rear deck 85 may support a motor bracket 101 consisting of a pair of metal legs 102 joined by bolts 103 and upwardly attaching flanges 104 to a plank 105 of sufficient thickness to receive the outboard clamp (Fig. 10). This motor supporting bracket may also have a depending metal strap 106 formed with an upwardly turned hook 107 of round stock, serving as a trunnion, for supporting the rudder 108. A similar hook 109 may be carried by the juncture of the stern panels 99, 100 adjacent their bottom; and the two hooks 107, 109 may serve as trunnions for receiving the U-shaped bearing members 110 carried by the rudder 108.

The rudder 108 may have a forwardly extending tiller handle 111; and the rudder should be of sufficient weight so that it will not be floated off the trunnions 107, 109.

Referring to Fig. 12, this shows the structure of the oar locks, which may be located rearwardly of the seats 92, 93. At these points the rails 84 may be reinforced by including an elongated block 112 between the flanges of the side frame members at their upper ends.

The block 112 may be provided with a downwardly extending bore 113 for receiving the shank 114 of an oar lock 115. The dotted line position of the top of the oar lock 115 shows the general shape of its arms, which embrace the shank of the paddle.

The present boat may thus be used as a row boat, an outboard boat, speed boat, a sail boat, or it may be equipped with an in-board motor. The curvature of the bottom is such that an in-board motor located amid-ships may have its shaft pass out of the bottom, forward of the stern, where the propeller would be located, and supported by means of a bearing bracket.

The upwardly pointed bow may have sufficient free board to ride over waves of reasonable size; and the bottom is so shaped that the boat will plane on top of the water when driven at a planing speed.

The boat presents a minimum resistance to

forward motion when rowing, but also presents a maximum lateral resistance against drifting. When equipped with the detachable keel, mast and sails, it provides a sail boat at minimum expense, which may be manufactured very economically and placed within the reach of a vast number of purchasers.

As a sail boat the present boat approximates the characteristics of a small sail boat of conventional design, having a weighted keel; and thus the present boat structure is perfect for all of the various fields of boating, and may be used interchangeably.

With this boat structure it will no longer be necessary to buy one boat especially for a speed boat and another especially for sailing and another for rowing, as all of these functions can be performed with a maximum efficiency by my boat.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A boat hull comprising a pair of longitudinally extending, substantially parallel keels forming bottom runners for the hull, a plurality of bottom frame members secured to and extending transversely to said keels, said transverse bottom frame members having straight upper edges separated by a web from two pairs of downwardly extending diagonal lower edge portions forming an apex at each runner and forming a concave obtuse angular edge portion between said runners, said web decreasing in width in successive transverse frame members as they are located successively closer to the bow and to the stern, and four plane bottom panels of sheet material secured to the lower edge portions of said transverse frame members and curved upwardly toward the bow and toward the stern forming a longitudinally curved inverted-V tunnel between the two runners, each

runner being mounted on a V-bottom portion, complementary obtuse angle strips secured above and below the junctures between said panels, upwardly extending side frame members carried by each end of each transverse frame member, said transverse frame members decreasing in length successively toward the bow and toward the stern, and two plane side panels carried by said side frame members and secured thereto in curved position, curving inward toward the bow and toward the stern and joined together at the bow and joined to the adjacent bottom panels, the juncture of said side panels and the adjacent bottom panels being closed inside and outside by two complementarily shaped angle strip members, and means for closing the stern of the hull.

2. A boat hull according to claim 1, in which the means for closing the stern of the hull comprises a pair of plane stern panels joined together at an obtuse angle at the mid-stern and joined to the bottom panels and side panels, the said stern panels and side panels being joined at the top by a deck portion of sheet material having a complementarily shaped edge.

JOHANNES H. WENDT.
